UNITED STATES PATENT OFFICE

154,510

DESIGN FOR A COMBINED SWITCH AND
FUSE PANEL BOARD

William Robertson, Detroit, Mich., assignor to
 Bull Dog Electric Products Company, Detroit,
 Mich., a corporation of West Virginia

Application May 27, 1948, Serial No. 146,642

Term of patent 14 years

(Cl. D26—13)

To all whom it may concern:

Be it known that a new, original, and ornamental Design for a Combined Switch and Fuse Panel Board has been invented by the undersigned who is a citizen of the United States, residing at Detroit, in the county of Wayne and State of Michigan, and the following is a specification, reference being had to the accompanying drawings, forming a part thereof.

Fig. 1 is an elevational view of a combined switch and fuse panel board with the cover removed showing my new design;

Fig. 2 is an elevational view of the right side of the above with part of the outer covering broken away and showing inner parts in section;

Fig. 3 is a sectional view taken on lines 3—3 of Fig. 1 with the fuse puller switches removed but with a cover shown in place;

Fig. 4 is an enlarged view in elevation of the base portion of the panel board only and with the left fuse puller switch removed.

Fig. 5 is a perspective view of a fuse puller

switch of which there are two in use with the base of Fig. 4 to form, with the box or cabinet, the panel board.

The configuration and form of the fuse puller switch of Fig. 5 is the dominant feature of the new design.

I claim:

The ornamental design for a combined switch and fuse panel board, substantially as shown and described.

WILLIAM ROBERTSON.
